US00D935245S

(12) **United States Design Patent** (10) **Patent No.:** **US D935,245 S**
(45) **Date of Patent:** **** Nov. 9, 2021**

(54) **BOOKSHELF**

(71) Applicant: **Shenzhen Aigelong Technology Co., Ltd.**, Shenzhen (CN)

(72) Inventor: **Liang Xiao**, Shenzhen (CN)

(**) Term: **15 Years**

(21) Appl. No.: **29/770,307**

(22) Filed: **Feb. 11, 2021**

(30) **Foreign Application Priority Data**

Feb. 1, 2021 (CN) 202130070281.9

(51) **LOC (13) Cl.** **06-06**

(52) **U.S. Cl.**

USPC **D6/675.1**

(58) **Field of Classification Search**

USPC D6/672, 675, 675.1, 675.2, 675.3, 675.4, D6/675.5, 682

CPC A47F 1/00; A47F 5/0018; A47B 96/00; A47B 96/02; A47B 47/00; A47B 47/042

See application file for complete search history.
